Albert N. Brooks, Chicago, Ill.

Application October 29, 1956, Serial No. 43,571

Term of patent 14 years

(Cl. D34—15)

Fig. 1.

Fig. 2.

Fig. 3.

Fig. 4.

Fig. 1 is a top plan view of a kaleidoscope showing my new design;

Fig. 2 is a side elevational view, the opposite side having substantially the same appearance;

Fig. 3 is an end elevation of the device, viewing it from the larger end; and

Fig. 4 is an end elevation of the device viewing it from the smaller end.

Portions of the drawing figures are diagonally lined to indicate transparency.

I claim:

The ornamental design for a kaleidoscope, substantially as shown and described.
